UNITED STATES PATENT OFFICE.

FRITZ ENSSLER, OF ROSELLE, NEW JERSEY.

NONELECTRIC IGNITER.

Application filed December 5, 1923. Serial No. 678,621.

To all whom it may concern:

Be it known that I, FRITZ ENSSLER, a citizen of Germany, residing at Roselle, county of Union and State of New Jersey, have invented certain new and useful Improvements in Nonelectric Igniters, of which the following is a specification.

My invention relates to improvements in non-electric igniters for use in gas combustion engines, being operated in conjunction with the compression created by the piston, most commonly used in the gas engine construction.

I attain these objects by the mechanism illustrated in the accompanying drawings, in which:

Figure 1 is a partial end elevation of a gas combustion engine, certain parts being broken away for clearness of illustration.

Figure 2 is an enlarged vertical section of the non-electric igniter and adjoining parts.

Figure 3 is an enlarged elevation of cylinder 10.

Figure 4 is a top plan view of Figure 3.

Figure 5 is an enlarged elevation of valve carrying cage 12.

Figure 6 is a top plan view of Figure 5.

Figure 7 is an enlarged elevation of block 4.

Figure 8 is a top plan view of Figure 7.

Figure 9 is an enlarged side elevation of shoulder bolt 8.

Figure 10 is a top plan view of Figure 9.

Figure 11 is an enlarged elevation of block 5.

Figure 12 is a top plan view of Figure 11.

Figure 13 is a top plan view taken on line A—A of Figure 1.

Similar numerals refer to similar parts throughout the several views.

Operating inside of cylinder 1 is the ordinary type reciprocating piston 2, operated by means of the well known type connecting rod and crankshaft.

Located central and on top of said piston 2, is a smaller piston 3, which is comprised of a cylindrical block 4, upper end of block 4 having countersunk groove 6, in which cylindrical block 5 with a shouldered end 7 fits, leaving a space 7^a, lower block 4 having four equally divided grooves 4^b which are connected to 7^a.

Blocks 4 and 5 being secured rigidly to piston 2 by means of shoulder bolt 8 and nut 9.

In direct alignment and above piston 3 is 55 a cylinder 10, said cylinder 10 being screwed into top of cylinder head of engine, said cylinder having cylindrical hole 11, which receives igniter piston 3, which enters said hole 11 when piston 2 reciprocates. 60

Cylinder 10 comprises a valve carrying cage 12, a valve 13 having a valve stem 14; rigidly secured to said valve stem is washer 15 slidably mounted in hole 16 of said cage 12; around valve 14 is a loosely fitting compression spring 17, the latter being held between washer 15 and bottom of hole 16; a slotted hole 18 in lower end of cylinder 10 is connected to a slotted hole 19 by means of canal 20. Directly above valve 13 is located a 70 collection chamber 21, which is joined to circular collection chamber 22 by means of openings 23, said circular collection chamber 22 being directly connected to cylinder chamber 11 by means of hole 22^a. 75

Fitting around outer circumference of valve cage 12 is an angle-shaped supporting bracket 24, the latter being held in a rigid position by means of a jam-nut 25. Pivotally mounted on upper end of said bracket 80 is a T-shaped lever 26, pivoted at 27^a in any suitable manner, the underside of said lever 26 resting on valve stem 14 and opposite end of lever 26 resting under a pair of rocker arms 27 and 28, the said rocker arms 27 and 28 also resting on the stem of exhaust valve 29 and intake valve 30, said exhaust valve 29 and intake valve 30 being of the well known type. The opposite ends of said rocker arms 27 and 28 respectively, resting 85 on push rods 31.

In operation and assuming the piston 2 to be traveling upward on the compression stroke, igniter piston 3 enters igniter cylinder chamber 11, thereby creating an over 90 compression, which is greatest when piston 2 arrives at nearly dead center.

The gas in said cylinder 10 is so greatly compressed that ignition takes place, the piston 2 arriving at dead center just after 100 the automatic ignition has taken place. At this instant, groove 7^a is directly opposite slot 18 in cylinder 10.

The ignited gases pass through slot 19 to adjoining channel 20, downwardly to slot 18, to circular groove 7^a which adjoins the four slot recesses 4^b in block 4 to the main cylinder chamber 1, thereby igniting the 105

compressed gases in main cylinder chamber 1 and consequently driving the piston 2 on its downward stroke. As soon as said piston 2 has reached its lowest dead center, the 5 exhaust valve 29 is opened by rocker arm 27, thereby allowing the already exhausted gases to be expelled through said exhaust valve 29 by the upward movement of piston 2. Also at the same instant exhaust valve 29 is 10 opened, valve 13 of the igniter is opened by the downward pressure of pivot lever 26 and as piston 3 enters cylinder chamber 11, there is no over compression, as the compressed air or gases passes by the opened 15 valve into the adjoining collection chamber 21, from there through openings 23 to collection chamber 22, thence passing through circular adjoining hole 22^a to cylinder chamber 1, thereby preventing high compression 20 ignition created within cylinder 10.

The exhaust valve 29 returns to its closed position while the intake valve 30 opens, thereby pressing the pivotally mounted lever 26 downward and opening valve 13, the 25 oncoming gas being drawn into the hole 22^a into igniter cylinder 11 in order to be ready for compression when exhaust valve 29, intake valve 30 and valve 13 closes, preparatory to the oncoming compression stroke; hence high compression again is created 30 within said cylinder 10 and ignition takes place, hence the process is constantly repeated.

Having thus described my invention what

I claim as new and desire to secure by Letters Patent of the United States is—

1. In an internal combustion engine, a cylinder, a main piston therein, an igniter piston carried by the main piston, an auxiliary cylinder arranged in line with and adapted to receive the igniter piston, a valve controlling admission of fuel to the auxiliary cylinder, a passage formed beyond and controlled by said valve to permit passage of compressed gas to return to the main cylinder on the non-explosive strokes of the main piston, and means for directly operating said valve.

2. In an internal combustion engine, a main cylinder, a main piston therein, an auxiliary piston carried by the main piston and formed with an annular channel and with outlet channels depending from and in communication with the annular channel, an auxiliary cylinder to receive the auxiliary piston, a port leading into said auxiliary cylinder near the upper end, a port communicating with the auxiliary cylinder near the lower end, a passage to establish communication between said ports, the auxiliary cylinder port near the lower end being positioned to communicate with the annular channel of the auxiliary piston when the latter has reached the limit of its stroke in one direction.

In testimony whereof I have affixed my signature.

FRITZ ENSSLE.
